(57) **CLAIM**

The ornamental design for a test paddle with handle, as shown and described.

DESCRIPTION

FIG. 1 is a perspective view taken from the top, back-end, and side of a test paddle with handle;

FIG. 2 is a top, front-end view thereof;

FIG. 3 is a front view thereof;

FIG. 4 is a back view thereof;

FIG. 5 is a side view thereof;

FIG. 6 is another side view thereof;

FIG. 7 is a front-end view thereof; and,

FIG. 8 is a back-end view thereof.

The broken line showing is for illustrative purposes only and forms no part of the claimed design.
